UNITED STATES PATENT OFFICE.

VALENTINE DEGENHARD, OF LINCOLN, ILLINOIS.

CORN-HARVESTER.

SPECIFICATION forming part of Letters Patent No. 690,841, dated January 7, 1902.

Application filed May 3, 1900. Serial No. 15,384. (No model.)

To all whom it may concern:

Be it known that I, VALENTINE DEGENHARD, a citizen of the United States, residing at Lincoln, in the county of Logan and State 5 of Illinois, have invented certain new and useful Improvements in Corn-Harvesters, of which the following is a specification.

This invention relates to new and useful improvements in corn-harvesters; and the object is to provide a device of this character which is adapted to direct, cut, and convey cornstalks to a binding mechanism and hold the bundles until a sufficient number has been accumulated in position on a platform convenient for removal to the ground.

To this end the invention consists in certain novel constructions of parts and their combinations, as will be hereinafter fully specified, and particularly and distinctly 20 pointed out in the claims.

I have fully and clearly illustrated the improvements in the accompanying drawings, wherein—

Figure 1 is a side elevation of the device. 25 Fig. 2 is a top plan view thereof with the guide-plates removed. Fig. 3 is a section on line xx , Fig. 2. Fig. 4 is a section on line yy , Fig. 1, with the beaters removed. Fig. 5 is a detail view of the fingers and their operating mechanism; and Fig. 6 is a section on line zz , Fig. 1.

Referring to said figures by characters of reference, 1 is a frame of any suitable construction, the top of which is preferably inclined downward and terminates in outwardly-curved ends 2, upon which are secured brackets 3, in which are journaled the lower ends of upwardly-inclined worms 4, which converge and are journaled at their 35 upper ends in brackets 5, secured to upwardly-inclined platforms 6, which extend to points adjacent to the binder. The upper ends of the worms 4 are provided with pinions 7, each of which meshes with a pinion 8, secured to the upper end of a shaft 9, which has its lower end journaled in the frame 1. One of these shafts 9 is provided with a worm 10, as shown, while secured to the opposite shaft is a beater 11, formed of two oppositely-arranged and 45 similar blades clamped to the shaft 9 and adapted to move therewith under ordinary conditions. The pinions 8 of the shafts 9 mesh with pinions 12, formed upon the ends of parallel worms 13, which are also journaled

in the brackets 5 and within sleeves 14, adjacent to their opposite ends. Secured to each worm 13 near the sleeve is a pinion 15, which meshes with a second pinion 16, mounted upon the platform 6 and engaging with a pinion 17, secured to the upper end of a shaft 18, suitably journaled within the platform 6 and having a pinion 19 at its lower end, which is adapted to receive motion from a pinion 20, secured to a shaft 21, which may receive motion from the traction-wheels of the binder or in any other suitable manner.

Beaters, as 22, are mounted upon the shafts 18 and movable therewith. These beaters are secured to the shafts in any desired manner, preferably by means of clamps 22^a, which will permit the same to move independently of the shafts when meeting any unusual obstructions. These clamps comprise ears 22^b, formed with the beaters and having eyes 70 therein for the reception of a bolt, which is not shown. (See Fig. 6.)

The lower end of each worm is preferably provided with a circular disk 23, as shown, to prevent clogging of the worms by rubbish, &c.

Inclined guide-plates, as 24, are preferably secured to brackets 25 at points above the worms 4 and 13, respectively.

Secured to the frame 1 and extending from a point below the upper ends of the worms 13 to the side of the device is a platform 26, to the inner side of which is secured a flat strip 27, curved rearward at its outer portion, as shown, and extending over and beyond a platform 28, fastened to the frame at a point below the plane of the platform 26. At the rear side of the platform 26 is secured a vertical shaft 29, having curved fingers 30, extending horizontally therefrom to points adjacent to the ends of the strip 27, and this shaft is suitably journaled in the frame. Adjacent to the lower end of the vertical shaft 29 is secured a horizontally-extending arm 31, the outer end of which is connected, by means of a rod 32, to a link 33, pivoted to a crank-arm 34, extending from a shaft 35, mounted in brackets 36, secured to the frame. This shaft is provided at its outer end with a crank-arm 37, and a spring 38 is secured to the frame and encircles the shaft 35, the free end thereof being secured to the crank-arm 34 and holding the same normally in lowered position.

The cutter and the binding mechanism may

be of any suitable character. They are indicated in Figs. 1 and 2 of the drawings by dotted lines, and reference being thereto had, *a* designates the driving or ground wheel, and *a'* the wheel on the opposite end of the axle and drive-shaft 21. On the shaft 21 is mounted a spool having a cam-race *b*, in which a pin in the end of a vibrating bar *c* loosely engages, the other end of the bar being pivotally connected to the outer end of the cutter-bar *d*, which actuates the cutter *f* in the usual manner.

The binding mechanism is of any proper construction. That conventionally indicated comprises a worm *n* on the driving-shaft 21, which meshes with a horizontally-placed bevel worm-pinion *m* on the face of the vertical shaft *k*, extending up through the hollow standard 29^a, and on the projecting part above the end of the hollow standard is the knotter-wheel *h* and the ejector-fingers *j*, the needle being indicated by the dotted lines *g*, Fig. 2, a tongue *i* being secured appropriately to the frame, substantially as indicated.

In operation it will be seen that the stalks will be conducted to the binder by means of the worms 4 and 13. The worm 4 moves in an opposite direction to the worm 13, and they both receive motion from the shaft 21 through shafts 18 and the pinions 15, 16, 17, 19, and 20. The revolution of the shafts 18 will at the same time cause the beaters to rotate toward the binder, and thereby throw the stalks within the worms 13, past the pinions 15, 16, and 17, into engagement with the balance of the worms. The stalks will be delivered from these worms to the binder, and the bundles will be discharged upon the platforms 26 and 28 between the fingers 30 and the strip 27. When a sufficient number of bundles has accumulated upon the platform, the same may be readily discharged to the ground by depressing the crank-arm 37, which will throw the arm 31 outward, turning the shaft 29 with its bearings and swinging the fingers 30 outward and away from the strip 27, when the bundles may be readily removed. When the crank-arm 37 is released, the fingers 30 will be returned to normal position through the force of the spring 38 operating the connections to the vertical shaft.

By means of the worm 10 stalks which are in an inclined position will be raised into engagement with the worms 4, and the beater 11 will throw the stalks from said worms 4 into engagement with the conveyers 13.

The worm 10 and the beater 11 receive their motion from the worms 13 through the gears 12 and 8, said gears also imparting motion to the worms 4.

In the foregoing description I have shown the preferred form of my invention; but I do not limit myself thereto, as I am aware that modifications may be made therein without departing from the spirit or sacrificing the advantages thereof, and I therefore reserve the right to make such changes and altera-

tions as may fairly come within the scope of my invention.

Having thus fully described my invention, what I claim as new, and desire to secure by Letters Patent, is—

1. In a device of the character described, the combination with a frame of inclined converging worms mounted thereon, parallel inclined worms journaled on the frame, means substantially as described for imparting rotation to said worms, a vertically-arranged worm disposed beneath the said worms at the upper ends of the converging worms, and a beater on a vertically-inclined shaft to coact with the adjacent worm, substantially as described.

2. In a device of the character described, the combination with a frame, of inclined and converging worms journaled thereon, pinions upon said worms, pinions meshing therewith, downwardly-extending shafts secured to said pinions, a worm upon one of said shafts, parallel inclined worms adapted to impart motion to the pinions of said shafts and means for imparting motion to said worms from a shaft.

3. In a device of the character described, the combination with a frame and axle of upwardly-extending shafts adapted to receive motion therefrom, beaters upon said shafts, pinions on the shafts, parallel inclined worms having pinions between their ends engaging said pinions, upwardly-inclined convergent worms, downwardly-extending shafts at the upper ends thereof, a beater upon one of the shafts, a worm upon the second shaft, and means for imparting motion from the parallel worms to said shafts and the converging worms.

4. In a device of the character described, the combination with a frame and an axle of upwardly-inclined converging worms downwardly-extending shafts at the upper ends thereof, a beater clamped upon one of said shafts, a worm upon the second shaft, parallel upwardly-inclined worms, beaters extending downwardly from each of said worms and means for imparting motion from the shaft to each of the beaters and worms, said worms adapted to revolve in opposite directions.

5. In a device of the character described, the combination with a frame having worm conveyers and beaters, of a platform thereon, a curved flat strip at one side thereof, a shaft journaled at one side thereof, fingers projecting from the shaft, an arm thereto, a shaft journaled within the frame, a crank thereto, a rod connecting said arm and crank, means for holding said crank, and an operating-crank at the opposite end of the shaft.

In testimony whereof I affix my signature in presence of two witnesses.

VALENTINE DEGENHARD.
